UNITED STATES PATENT OFFICE

THEODORE K. VOGELEY, OF BUTLER, PENNSYLVANIA

APPARATUS FOR MINING

Application filed February 28, 1929. Serial No. 343,304.

My invention relates to a method of and apparatus for mining, and particularly for the mining of coal.

One object of my invention is to provide a means and a method whereby a defined block of coal from a coal seam may be cut, broken down and loaded in an economical manner, with a large percentage of lump coal and with a small amount of damage to the mine 10 roof.

My invention is more particularly adapted for use in connection with the long-wall system of mining coal, although a short-wall mining machine may be employed in such 15 long-wall mining operation.

One form of apparatus and system for practising my invention is shown in the accompanying drawing wherein Figure 1 is a 20 partially diagrammatic view showing the apparatus in plan; Fig. 2 is a plan view, on an enlarged scale, of a portion of the apparatus of Fig. 1, and Fig. 3 is a view of a portion of the apparatus of Fig. 1, in end elevation, and on an enlarged scale.

25 By the arrangement shown in the drawing, entries 4 and 5 are provided in the coal seam and headers 6 communicate therewith, an additional header or entry 7 being driven into the coal seam to permit placing of the cutting machine and conveyors. The entries and 30 headers define blocks of coal 8 which it is desired to mine.

The cutting machine is represented by the 35 numeral 10, and 11 represents a receiving conveyor. The frame of the conveyor 11 and the cutting machine 10 are shown as pivotally connected at 12, but may be connected for unitary traveling movement in any other suitable manner. The conveyor 11 is mounted 40 on a sled carriage 9 so that the apparatus can be moved along the face of the block of coal, as the cutting and breaking down of the coal progresses. This movement is effected in any suitable manner, as for instance by a cable 13 whose one end is anchored at 14 and which passes around a sheave 15 to a winding drum 16 that is driven by the motor of the cutting machine.

The belt of the conveyor 11 is driven by a 50 motor 17, through the medium of a sprocket

wheel 18, a sprocket chain 19, and a sprocket wheel 20. The conveyor is of such small vertical dimension at its inner or forward end as to permit entry thereof into the kerf which is cut by the cutting machine 10.

55 In the operation of the system, the cutting machine is advanced along the face of the coal by means of the winding drum 16 and the cable 13 referred to, during operation of the cutting machine. Previous to or during the cutting of the coal, shot holes 21 may be drilled at the upper side of the coal seam so that when the cutting has progressed to a point where the conveyor 11 extends a desired distance into the kerf, explosives are 60 introduced into the holes 21 to shoot down the mass of undermined coal upon the conveyor, the explosive charge being sufficient to break up the coal into lumps small enough to be conveniently carried by the conveyor. It will be seen that although only a single 65 kerf is cut in the coal seam, the explosive charge need not be so great as to produce any considerable quantity of pulverized coal, since such undercut portion of the coal has 70 two exposed vertical faces as compared to short wall systems wherein only one face (the outer face) of the undermined coal is exposed.

75 A plate 30 is supported by the conveyor 11 and bridges the space between the cutter chain and the conveyor to prevent loose coal from falling therebetween and interfering with the advancing movement of the conveyor into the kerf. As shown in Fig. 2, the right hand flight of the cutter chain will carry loose coal out of the path of travel of the conveyor frame to permit the frame to be freely moved into the kerf.

80 The receiving conveyor 11 discharges to a face conveyor 22 which in turn discharges to a section conveyor 23. From the section conveyor, the coal is discharged upon a transfer conveyor 24 which in turn discharges the coal into mine cars 25. Main entry conveyors 85 26 are provided for carrying coal to the transfer conveyor 24, from other headers.

85 The spacing between the conveyor 11 and the cutting machine 10, as indicated in Fig. 3, will depend upon the nature of the coal and 90

the thickness of the vein, as well as upon the width and capacity of the conveyer. For thick veins of coal and relatively narrow conveyers, the coal will have to be shot down before the conveyer has entered too far into the kerf, so that the conveyer will properly handle the coal shot down. Ordinarily, the cutting machine will be stopped during shooting operations.

16 The arrangement above-described possesses the further advantage that since the entire exposed upper face of the conveyer belt travels towards the discharge end of the conveyer, a deeper kerf may be cut into the coal seam and then shot down than if the conveyer flights were disposed in horizontally-spaced relation instead of vertically-spaced relation, since in the case of horizontally-spaced flights, a portion of the coal would be caught by the outer conveyer flight and carried toward the face of the coal seam.

15 In other words, not only may the tonnage mined be increased with my conveyer arrangement by reason of the increased depth of cut possible, but all coal which falls upon the conveyer will be carried toward the discharge end thereof.

20 A further advantage of my arrangement of the cutting machine and the conveyer resides in the pivotal connection therebetween, since unitary travelling movement is obtained thereby without danger of the apparatus binding in the kerf. The weight of the conveyer mechanism and the coal carried thereby is not imposed upon the cutter frame by any unevenness in the floor or by any particles of coal, as would be the case if the cutter and the conveyer were solidly connected together. By providing detachable connection between 25 the cutter and conveyer, they may be independently transported or moved into operative position and connected together.

40 I claim as my invention:

1. Mining apparatus comprising a frame, 45 a cutter chain of loop form movable around said frame, a conveyer frame disposed alongside of the first-named frame and having pivotal connection therewith on a horizontal axis extending longitudinally of the 50 said frames, and a conveyer movable on said conveyer frame.

2. Mining apparatus comprising an undercutting machine, a conveying device disposed with its longitudinal axis in parallelism with 55 said undercutting machine, and means for detachably connecting said undercutting machine with said conveying device at points spaced longitudinally thereof, whereby said device and said machine are rendered capable 60 of relative vertical movements independently of each other.

3. Mining apparatus comprising a cutting device for cutting kerfs movable in a horizontal plane, a belt conveyer disposed to the 65 rear of the cutting device and having upper

and lower runs disposed within the upper and lower boundary lines of the cutting device, means for advancing the cutting device and the conveyer into a coal seam, and means pivotally connecting said device and said conveyer at points spaced longitudinally therebetween, whereby the conveyer is rendered capable of relative vertical movements independently of the cutting device during advancing movement into the coal seam.

In testimony whereof I, the said THEODORE K. VOGELEY, have hereunto set my hand.

THEODORE K. VOGELEY.
